[57] ABSTRACT

An electronic musical instrument employing a sampling system as a coupler for obtaining a musical tone by coupling a plurality of tone signals together. The system includes sampling circuits each adapted for sampling with a control signal an input signal applied from a corresponding tone generator which generates a tone signal or from a corresponding envelope circuit which delivers a depression— responsive signal in response to closure of a key switch of the musical instrument, square waveform voltage generators each generating a square waveform voltage as the control signal to the sampling circuit, and duty ratio varying circuits connected to respective square waveform voltage generators for varying the duty ratio of the square waveform voltage so as to vary the magnitude of the output signal of the sampling circuit.

ELECTRONIC MUSICAL INSTRUMENT EMPLOYING A SAMPLING SYSTEM AS A COUPLER

This is a continuation, of application Ser. No. 69,397, filed Sept. 3, 1970, now abandoned.

This invention relates to a coupler system for use in an electronic musical instrument such as an electronic organ for producing simultaneously the tones spaced apart by octave relation in the same keyboard or the same tones or tones spaced apart by octave relation in a plurality of keyboards such as an upper and a lower keyboards. More particularly, the present invention relates to a coupler system which takes advantage of the pulse technique so that the degree or mixing of a plurality of tones to be coupled together can be varied as desired.

It is an object of the present invention to provide a system capable of easily varying the degree of coupling of tones.

Another object of the present invention is to provide a system capable of easily varying the degree of coupling of tones in an electronic musical instrument of the direct keying type in which the transmission of a tone signal to the following circuit is directly controlled by a key switch.

A further object of the present invention is to provide a system capable of easily varying the degree of coupling of tones in an electronic musical instrument of the indirect keying type in which the transmission of a tone signal to the following circuit is indirectly controlled by controlling a gate by a control signal obtained in response to manipulation of a key switch.

A still further object of the present invention is to provide, in an electronic musical instrument of the indirect keying type having two or more keyboards, a system in which, in response to depression of a key switch in one of the keyboards for producing a tone, a tone same as the tone produced by the depression of the key switch or a tone in octave relation with the above tone can be simultaneously produced from another keyboard, and yet the degree of coupling of these tones can be easily varied.

A yet further object of the present invention is to provide a system capable of easily varying the degree of coupling of tones in an electronic musical instrument of the indirect keying type provided with a touch-sensitive function so that the volume of a tone is variable depending on the rate of depression of the key of a key switch, that is, the intensity of striking the key.

These and other objects, features and advantages of the present invention will be made clear from the following detailed description of preferred embodiments thereof taken in conjunction with the accompanying drawings, in which:

FIG. 1 is a circuit diagram of one form of sampling means employed in the present invention;

FIGS. 2, 3, 4 and 5 are graphic representations of signal waveforms appearing at various parts of the circuit shown in FIG. 1;

FIGS. 6, 7, 8 and 9 are circuit diagrams of parts of some embodiments of the present invention preferably used in an electronic musical instrument of the direct keying type;

FIG. 10 is a block diagram of parts of an embodiment of the present invention preferably used in an electronic musical instrument of the indirect keying type;

FIGS. 11, 12 and 13 are graphic representations of signal waveforms for illustrating the operation of the embodiment shown in FIG. 10;

FIG. 14 is a block diagram of parts of another embodiment of the present invention preferably used in an electronic musical instrument of the indirect keying type;

FIG. 15 is a circuit diagram of a touch-sensitive effect circuit preferably used in the system according to the present invention;

FIG. 16 is an example of a circuit diagram of a square waveform generator for generating a square waveform whose duty ratio is variable; and

FIGS. 17a, 17b, 17c and 17d are graphic representations of signal waveforms appearing at various parts of the generator shown in FIG. 16.

A sampling means employed in the present invention will be described with reference to FIGS. 1 to 5 before giving detailed description as to application of a coupler system of the present invention to an electronic musical instrument of the direct keying type.

Referring to FIG. 1, resistors R_1 and R_2 are connected in series between an input terminal 1 and an output terminal 4, and a diode D_1 is connected between a control terminal 2 and the junction point 3 of the resistors R_1 and R_2 , while a capacitor C_1 is connected between the output terminal 4 and ground. A tone signal e_1 having a waveform as shown in FIG. 2 is applied to the input terminal 1 of the sampling means having a structure as shown in FIG. 1. A control signal e_2 having a waveform as shown in FIG. 3 is applied to the control terminal 2 of the sampling means. The control signal e_2 has a repetition frequency sufficiently higher than the frequency of the tone signal e_1 and the maximum value V_2 of the control signal e_2 is greater than the maximum value V_1 of the tone signal e_1 . Now, the signal appearing at the junction point 3 between the diode D_1 and the resistors R_1 and R_2 will be discussed. When the maximum voltage V_2 is applied to the control terminal 2, the diode D_1 is reverse biased and is not conducting due to $V_1 < V_2$ so that the tone signal applied to the input terminal 1 is passed through the resistor R_1 to appear at the junction point 3. Then, when the voltage applied to the control terminal 2 is reduced to zero volt, the diode D_1 is forward biased to conduct and the voltage at the junction point 3 is forcedly reduced to zero volt. In this manner, the diode D_1 is turned on and off at the same frequency as the repetition frequency of the control signal e_2 applied to the control terminal 2, and as a result, a signal e_3 having a waveform as shown in FIG. 4 appears at the junction point 3. The signal e_3 having such a waveform is integrated by the resistor R_2 and the capacitor C_1 so that a signal e_4 having a waveform as shown in FIG. 5 which is analogous to the waveform of the tone signal e_1 applied to the input terminal 1 appears at the output terminal 4. It will be seen from FIG. 5 that the amplitude of the output signal e_4 can be varied by varying the duty ratio T/T of the control signal e_2 .

Referring to FIG. 6 showing an embodiment of the present invention, a plurality of such circuits are provided for a 4-ft. tone signal, an 8-ft. tone signal and a 16-ft. tone signal, respectively. Outputs of these circuits are connected to mixing resistors R_3 and R_4 and then to ground through a D.C. blocking capacitor C_2 and a charging resistor R_5 . The junction point between the capacitor C_2 and the resistor R_5 is connected to a

movable contact 6 of a key switch 5, and the control terminals 2a, 2b and 2c are connected to respective sources of 4-ft., 8-ft. and 16-ft. control signals. Thus, by varying the duty ratio of the control signals applied to the control terminals 2a, 2b and 2c, that is, by varying the period of time of sampling of these tone signals, the relative intensities of the components of the tone signal appearing at the movable contact 6 of the key switch 5 can be regulated entirely independently of each other on the basis of the principle described above.

FIG. 7 shows another embodiment of the present invention in which the relative position of the resistor R₁ and the diode D₁ shown in FIG. 6 is interchanged so that the diode D₁ is disposed in the path of each of the 4-ft., 8-ft. and 16-ft. tone signals. The embodiment shown in FIG. 7 is based on the entire same principle as that of the embodiment shown in FIG. 6. Herein, the relation described with reference to FIG. 1 also holds between the tone signal and the control signal. When the voltage V₂ (V₂ < V₁) is applied to each of the control terminals 2a, 2b and 2c, the diode D₁ is forward biased to conduct so that the tone signal applied to the input terminal appears at the junction point 3 between the diode D₁ and the resistors R₁ and R₂. Then, when the voltage applied to the control terminal 2 is reduced to zero volt, the diode D₁ is reverse biased to be cut off so that no tone signal appears at the junction point 3. Thus, the diode D₁ is turned on and off with the same frequency as the repetition frequency of the control signal applied to the control terminal 2. As a result, signals having a waveform as shown in FIG. 4 appear at the junction point 3 as in the case of FIG. 6.

While the embodiments shown in FIGS. 6 and 7 are so arranged that the 4-ft., 8-ft. and 16-ft. tone signals are sampled relative to the time axis and are then integrated and mixed, these tone signals may be sampled relative to the time axis and then mixed and integrated as shown in FIGS. 8 and 9 to obtain the result similar to FIGS. 6 and 7. This latter case is advantageous in that the number of circuit elements can be reduced compared with the former case.

It will be understood from the above description that the present invention provides many advantages when it is used in an electronic musical instrument of the direct keying type. That is, the system can provide a tone color which is solemn and variable over a wide range due to the fact that the relative intensities of 4-ft., 8-ft. and 16-ft. tone signals can be regulated by a single key switch without the use of a plurality of key switches employed heretofore, and at the same time, the problems encountered with the provision of a plurality of contacts including the need for adjustment of the position of these contacts and the reliability of the contacts for attaining the simultaneous on-off of a plurality of switches can be completely eliminated. Further, the tone signal is not limited to the sine waveform but it may have any desired waveform such as a square waveform, triangular waveform or saw-tooth waveform.

Another embodiment of the present invention will be described with reference to FIG. 10 to illustrate an application thereof to an electronic musical instrument of the indirect keying type.

Referring to FIG. 10, tone generators 8a, 8b, 8c, 8d and 8e generate tone signals corresponding to the notes C₁, C₂, C₃, C₄ and C₅, respectively. Gate circuits 7a, 7b, 7c, 7d and 7e are connected to the respective tone generators 8a, 8b, 8c, 8d and 8e. Envelope circuits 12a,

12b, 12c, 12d and 12e are provided for the respective gate circuits 7a, 7b, 7c, 7d and 7e and are connected to the respective key switches 13a, 13b, 13c, 13d and 13e. A D.C. power supply 14 supplies a D.C. voltage to the envelope circuits 12a, 12b, 12c, 12d and 12e through the respective key switches 13a, 13b, 13c, 13d and 13e. 8-ft. sampling circuits 10a, 10b, 10c, 10d and 10e similar to that shown in FIG. 1 are connected between the envelope circuits 12a, 12b, 12c, 12d and 12e and the corresponding gate circuits 7a, 7b, 7c, 7d and 7e, respectively. The control terminals 2 of these sampling circuits 10a, 10b, 10c, 10d and 10e are connected in common to the output terminal of an 8-ft. square waveform generator 16. 16-ft. sampling circuits 11a, 11b, 11c, 11d and 11e similar to that shown in FIG. 1 are connected between the envelope circuits 12a, 12b, 12c, 12d and 12e, and a gate circuit (disposed on the left-hand side of the gate circuit 7a) and the gate circuits 7a, 7b, 7c and 7d, respectively. The control terminal 2 of these sampling circuits 11a, 11b, 11c, 11d and 11e are connected in common to the output terminal of a 16-ft. square waveform generator 17. 4-ft. sampling circuits 9a, 9b, 9c, 9d and 9e similar to that shown in FIG. 1 are connected between an envelope circuit (disposed on the left-hand side of the envelope circuit 12a) and the envelope circuits 12a, 12b, 12c and 12d and the gate circuits 7a, 7b, 7c, 7d and 7e, respectively. The control terminals 2 of these sampling circuits 9a, 9b, 9c, 9d and 9e are connected in common to the output terminal of a 4-ft. square waveform generator 15. The input and output terminals of all these sampling circuits are designated by the reference numerals 1 and 4, respectively.

In operation, when a desired key is depressed, the envelope circuit corresponding to the depressed key is energized to generate a depression-responsive signal e₅ having a waveform as shown in FIG. 11 and this signal is applied to the sampling circuits connected to the envelope circuit. When, for example, the key switch 13c is turned on, the depression-responsive signal e₅ is applied to the input terminals 1 of the sampling circuits 9d, 10c and 11c from the envelope circuit 12c. Square waveform voltage e₂ as shown in FIG. 3 are applied to the control terminals 2 of the sampling circuits 9d, 10c and 11c from the respective square waveform generators 15, 16 and 17. The relation V₅ < V₂ holds between the maximum value V₅ of the depression-responsive signal e₅ and the maximum value V₂ of the square waveform voltage e₂. Thus, in response to the application of the voltage V₂ (V₂ > V₅) to the control terminal 2 of each of the sampling circuits 9d, 10c and 11c, the diode D₁ is reverse biased to be cut off so that the depression-responsive signal applied to the input terminal 1 is passed through the resistor R₁ to appear at the junction point 3 in the manner described with reference to FIG. 1. Then, when the voltage e₂ applied to the control terminal 2 is reduced to zero volt, the diode D₁ is forward biased to conduct so that the voltage appearing at the junction point 3 is forcedly reduced to zero volt. As a result, a signal e₆ having a waveform as shown in FIG. 12 appears at the junction point 3. A signal e₇ having a waveform as shown in FIG. 13 which is analogous to that of the depression-responsive signal e₅ applied to the input terminal 1 appears at the output terminal 4 when the signal waveform e₆ is integrated by the resistor R₂ and capacitor C₁. The amplitude of the signal e₇ can be varied by varying the duty ratio τ/T of the con-

trol signal e_2 applied to the control terminal 2. Thus, according to the arrangement shown in FIG. 10 in which the 4-ft., 8-ft. and 16-ft. square waveform generators 15, 16 and 17 are separately provided so that the duty ratios of the square waveforms can be varied independently of one another, the depression-responsive signal delivered from the envelope circuit 12c and applied to the sampling circuits 9d, 10c and 11c is transformed according to the duty ratios of the square waveforms supplied from the square waveform generators 15, 16 and 17, and the transformed signals are applied to the associated gate circuits to obtain the tone signals. Suppose, for example, that the duty ratio of the square waveforms supplied from the 4-ft., 8-ft. and 16-ft. square waveform generators 15, 16 and 17 are 1, 0 and $\frac{1}{2}$, respectively. Then, in response to the depression of the key switch 13c, the envelope circuit 12c associated with the key switch 13c is energized to apply the depression-responsive signal to the three sampling circuits 9d, 10c and 11c. The depression-responsive signal passed through the 4-ft. sampling circuit 9d has an amplitude corresponding to $\tau/T = 1$ and appears at the control terminal of the gate circuit 7d for the note C_4 , with the result that the gate circuit 7d is opened and the tone signal corresponding to the note C_4 is delivered from the output terminal of the gate circuit 7d. The depression-responsive signal applied to the 8-ft. sampling circuit 10c cannot pass therethrough with the result that the gate circuit 7c is not opened and the tone signal corresponding to the note C_3 does not appear. The depression-responsive signal passed through the 16-ft. sampling circuit 11c has an amplitude corresponding to $\tau/T = \frac{1}{2}$ which is the half of the amplitude of the signal passed through the 4-ft. sampling circuit 9d. As a result, the gate circuit 7b for the note C_2 is half opened to deliver the tone signal corresponding to the note C_2 , but this tone signal has an amplitude which is half of the amplitude of the tone signal corresponding to the note C_4 .

It will be understood from the above description that the present invention provides many advantages when it is applied to an electronic musical instrument of the indirect keying type. That is, a single switch instead of a plurality of key switches can attain the desired coupling of tone signals, and the number of gate circuits may merely be equal to the number of tone sources in contrast to the prior art method in which the gate circuits whose number is equal to the number of feet are required for each key switch. Further, the present invention eliminates the prior defect of incapability of independently adjusting the volume of the respective feet. According to the present invention, the volume of the respective feet can be continuously varied by varying the duty ratio of the square waveforms used for the sampling of the depression-responsive signal. Thus, all the problems encountered with the provision of a plurality of contacts including the need for adjustment of the position of these contacts for attaining the simultaneous on-off of a plurality of contacts, the reliability of the contacts and the high cost due to the complex structure can be solved without degrading the performance of the musical instrument. In the arrangement shown in FIG. 10, the integrating capacitor C_1 (FIG. 1) is incorporated in each of the sampling circuits so as to carry out the integration in each sampling circuit. However, the capacitor C_1 in the circuit shown in FIG. 1 may be removed and connected to the output side of

a plurality of such sampling circuits so as to reduce the number of parts.

An embodiment of a keyboard coupler system according to the present invention will be described with reference to FIG. 14. Referring to FIG. 14, the stationary contacts of a key switch 24 is an upper keyboard 23 and a key switch 24' in a lower keyboard 23' are connected to the positive terminal of a D.C. power supply 14 whose negative terminal is grounded. The movable contacts of the key switches 24 and 24' are connected to an envelope circuit 28 associated with the upper keyboard 23 and an envelope circuit 28' associated with the lower keyboard 23', respectively.

The envelope circuit 28 is connected to a resistor R_8 and to the input terminal 1 of a sampling circuit 25 connecting the circuit of the upper keyboard 23 to the circuit of the lower keyboard 23'. The envelope circuit 28' is connected to a resistor R_8' and to the input terminal 1' of a sampling circuit 25' connecting the circuit of the lower keyboard 23' to the circuit of the upper keyboard 23. Square waveform generators 29 and 29' generating a square waveform voltage as shown in FIG. 3 are connected to the control terminals 2 and 2' of the sampling circuits 25 and 25', respectively. The square waveform generators 29 and 29' are grounded at the other terminal thereof. The sampling circuits 25 and 25' have a structure as shown in FIG. 1. The output terminal 4 of the sampling circuit 25 is connected to the resistor R_8 and to the control terminal of a gate circuit 27' associated with the lower keyboard 23', while the output terminal 4' of the sampling circuit 25' is connected to the resistor R_8' and to the control terminal of a gate circuit 27 associated with the upper keyboard 23. A tone signal is supplied to the input terminal of the gate circuit 27 associated with the upper keyboard 23 from a tone generator 26, while another tone signal is supplied to the input terminal of the gate 27' associated with the lower keyboard 23' from a tone generator 26'. When a required voltage appears at the control terminals of the gate circuits 27 and 27', the gate circuits 27 and 27' are opened to deliver the tone signals to their output terminals 30 and 30', respectively.

When a desired key in the upper keyboard 23 is depressed to close the key switch 24 corresponding to the key, the voltage E of the D.C. power supply 14 is applied to the envelope circuit 28 associated with the upper keyboard 23. Then, when the force applied to the key is released in a certain period of time, a depression-responsive signal as shown in FIG. 11 is applied from the envelope circuit 28 to the control terminal of the gate circuit 27 through the resistor R_8 . As a result, the gate circuit 27 is opened and the tone signal supplied from the tone generator 26 appears at the output terminal 30 of the gate circuit 27. At the same time, the depression-responsive signal delivered from the envelope circuit 28 associated with the upper keyboard 23 is applied to the input terminal 1 of the sampling circuit 25. In response to the application of the depression-responsive signal having a waveform as shown in FIG. 11 from the envelope circuit 28 and the square waveform voltage having a waveform as shown in FIG. 3 from the square waveform generator 29 to the input terminal 1 and control terminal 2, respectively, of the sampling circuit 25 having a structure as shown in FIG. 1, a waveform as shown in FIG. 12 appears at the junction point 3 between the diode D_1 and the resistors R_1 and R_2 due to the on-off of the diode D_1 and is inte-

grated by the resistor R_2 and the capacitor C_1 so that a signal having a wave-form as shown in FIG. 13 appears at the output terminal 4 of the sampling circuit 25. This signal is applied to the control terminal of the gate circuit 27' associated with the lower keyboard 23' to open the gate circuit 27' so that the tone signal supplied from the tone generator 26' appears at the output terminal 30' of the gate circuit 27'. The amplitude of the signal appearing at the output terminal 4 of the sampling circuit 25 can be varied by varying the duty ratio τ/T of the square waveform supplied from the square waveform generator 29. It is possible, therefore, to vary the amplitude of the tone signal appearing at the output terminal 30' of the gate circuit 27' associated with the lower keyboard 23' thereby to adjust the degree of coupling of the tone produced from the lower keyboard 23' to the tone produced from the upper keyboard 23.

When a key in the lower keyboard 23' is depressed to close the key switch 24' corresponding to the key, the voltage E of the D.C. power supply 14 is applied to the envelope circuit 28' associated with the lower keyboard 23'. Then, when the force applied to the key is released in a certain period of time, a depression-responsive signal as shown in FIG. 11 is applied from the envelope circuit 28' to the control terminal of the gate 27' through the resistor R_8 . As a result, the gate 27' is opened and the tone signal supplied from the tone generator 26' appears at the output terminal 30' of the gate 27'. At the same time, the depression-responsive signal delivered from the envelope circuit 28' associated with the lower keyboard 23' is applied to the input terminal 1' of the sampling circuit 25'. In response to the application of the depression-responsive signal having a waveform as shown in FIG. 11 from the envelope circuit 28' and the square waveform voltage having a waveform as shown in FIG. 3 from the square waveform generator 29' to the input terminal 1' and control terminal 2', respectively, of the sampling circuit 25' having a structure as shown in FIG. 1, a signal having a waveform as shown in FIG. 13 appears at the output terminal 4' of the sampling circuit 25'. This signal is applied to the control terminal of the gate 27 associated with the upper keyboard 23 to open the gate 27 so that the tone signal supplied from the tone generator 26 appears at the output terminal 30 of the gate 27. In this case too, the amplitude of the signal appearing at the out-put terminal 4' of the sampling circuit 25' can be varied by varying the duty ratio τ/T of the square waveform supplied from the square waveform generator 29'. It is possible, therefore, to vary the amplitude of the tone signal appearing at the output terminal 30 of the gate 27 associated with the upper keyboard 23 thereby to adjust the degree of coupling of the tone produced from the upper keyboard 23 to the tone produced from the lower keyboard 23'. A keyboard coupler system can thus be realized. The keyboard coupler system based on the above method does not require additional provision of key switches, and therefore, eliminates the problems encountered with the prior art arrangement including the simultaneous on-off of switches, the need for adjustment of the position thereof and the reduction in the reliability of the switches due to the increase in the number of the key switches. Further, the degree of coupling of the tones produced from the keyboards can be continuously var-

ied by regulating the duty ratio τ/T of the waveform generated by the square waveform generators.

It will be understood from the foregoing description that the present invention eliminates many problems as described above encountered with the prior art coupler system when it is applied to electronic musical instruments of both the direct and the indirect keying type. Especially, the coupler system according to the present invention is indispensable in an electronic musical instrument of the kind which will be described below.

An important feature of the sampling circuit forming the essential part of the coupler system according to the present invention shown in FIG. 1 resides in the fact that the voltage appearing at the output terminal 4 is proportional to the voltage supplied to the input terminal 1 within the range of $0 \leq V_1 \leq V_2$ (FIGS. 2 and 3), and is also proportional to the duty ratio τ/T of the square waveform supplied to the control terminal 2. A system utilizing the proportional relation between the output and input voltage will now be described.

Musical instruments presently in use include an instrument such as a cembalo which produces a tone whose volume is constant independently of the strength of touching the key and an instrument such as a piano which produces a tone whose volume is variable depending on the strength of striking the key. While the former musical instrument produces a very delicate and beautiful tone color, it has a drawback that the volume of the tone does not vary depending on the key striking force, and it is said that the piano is developed to take the place of the cembalo. Looking back to the history of these musical instruments, it is apparent that the future tendency of electronic musical instruments is toward the capability of producing a variable tone volume or tone color depending on the key striking force or key striking rate.

Such a demand can be met by the use of an envelope circuit as shown in FIG. 15 in an electronic musical instrument of the indirect keying type so that the electronic musical instrument can produce a tone whose volume is variable depending on the key striking rate. Referring to FIG. 15, a key switch includes a normally closed stationary contact 31, a movable contact 32 and a normally open stationary contact 33. In this key switch, the so-called contact transition time required for the movable contact 32 to contact the normally open stationary contact 33 after it is urged away from the contact with the normally closed stationary contact 31 becomes shorter with a higher key striking speed, while the contact transition time becomes longer with a lower key striking speed. The normally closed stationary contact 31 is connected to the negative terminal of a D.C. power supply 14, while the normally open stationary contact 33 is connected to the positive terminal of the D.C. power supply 14, and at the same time, to ground. The movable contact 32 is connected through a parallel circuit of a capacitor C_5 and a resistor R_9 to an output terminal 34 which is connected to the cathode of a diode D_3 whose anode is grounded. In the position in which the key is not depressed, the capacitor C_5 is charged to E volts from the D.C. power supply 14 through the diode D_3 , movable contact 32 and normally closed stationary contact 31, with the capacitor terminal connected to the output terminal 34 being positive relative to the other terminal connected to the movable contact 32. Then, when the key is depressed in the above state to urge the movable contact 32 away

from the normally closed stationary contact 31, the voltage charged in the capacitor C_5 starts to discharge through the resistor R_9 , but no voltage appears yet at the output terminal 34.

In a suitable period of time, the movable contact 32 is brought into contact with the normally open stationary contact 33 and the voltage across the capacitor C_5 appears at the output terminal 34. When the transition time for the movable contact 32 is short, the voltage charged in the capacitor C_5 is not discharged so much through the resistor R_9 and a relatively large voltage appears at the output terminal 34 when the movable contact 32 is brought into contact with the normally open stationary contact 33. When, however, the transition time is long, the voltage charged in capacitor C_5 is sufficiently discharged through the resistor R_9 and a very small voltage appears at the output terminal 34 when the movable contact 32 is brought into contact with the normally open stationary contact 33. That is, with a high key striking speed, hence with a short transition time, a large voltage appears at the output terminal 34, while with a low key striking speed, hence with a long transition time, a small voltage appears at the output terminal 34. The circuit shown in FIG. 15 may be employed in place of the key switches 13a, 13b, 13c, 13d and 13e and the envelope circuits 12a, 12b, 12c, 12d and 12e in the system shown in FIG. 10. It will be recalled that there is a proportional relation between the signal delivered from the envelope circuits 12a, 12b, 12c, 12d and 12e and the signal applied to the gate circuits 7a, 7b, 7c, 7d and 7e, that is, there is a proportional relation between the input to and the output from the sampling circuits 9a, 9b, 9c, 9d, 9e; 10a, 10b, 10c, 10d, 10e; and 11a, 11b, 11c, 11d, 11e. Therefore, any variation in the output voltage delivered from the envelope circuits 12a, 12b, 12c, 12d and 12e depending on the key striking speed results in the corresponding variation in the signal applied to the gate circuits 7a, 7b, 7c, 7d and 7e so that tone signals of large amplitude appear at the output terminals of the gate circuits in response to a high key striking speed, while tone signals of small amplitude appear at the output terminals of the gate circuits in response to a low key striking speed. In a coupler system for use in an electronic musical instrument in which the amplitude of the depression responsive signal is variable depending on the key striking speed, there must be a linearity between the amplitude of the input and the amplitude of the output. In this respect too, the coupler system according to the present invention is quite excellent.

The square waveform generator capable of generating a square waveform whose duty ratio τ/T is variable can be offered in several forms. One form of such square waveform generator is shown in FIG. 16, and this square waveform generator is so arranged as to vary the duty ratio depending on the magnitude of a D.C. voltage. Referring to FIG. 16, the square waveform generator includes a differential amplifier composed of two transistors Tr_1 and Tr_2 . When a saw-tooth waveform voltage as shown in FIG. 17a is applied to the base of one of the transistors Tr_1 and a D.C. voltage V_a is applied to the base of the other transistor Tr_2 , the output appearing at the collector of the transistor Tr_2 has a waveform as shown in FIG. 17b from which it will be seen that the portion of the saw-tooth waveform above the level V_a is solely greatly extended. This waveform is then shaped by a Schmitt circuit composed

of two transistors Tr_3 and Tr_4 to obtain a waveform as shown in FIG. 17c. The waveform thus obtained is amplified to a required amplitude and shaped by a transistor Tr_5 , the resulting waveform being then passed through an emitter follower including a transistor Tr_6 to obtain a signal as shown in FIG. 17d. It will be apparent that the duty ratio τ/T of the waveform derived from the emitter of the transistor Tr_6 can be continuously varied within the range of 0 to 1 by varying the D.C. voltage V_a .

While the foregoing description has referred to a system in which a diode is used as the switching element in the sampling circuit, the switching element is in no way limited to the diode, and a transistor, electronic tube or the like may be employed in lieu of the diode for exhibiting the performance similar to that attained by the sampling circuit. Further, the operation entirely the same as that described above can be carried out by reversing the polarity of all the circuit components including the diode and power supply. Furthermore, the foregoing description has referred to a coupler system including couplers for the 16-ft., 8-ft. and 4-ft. tone signals, but it will be readily apparent that the present invention is similarly applicable to a coupler system including couplers for the 32-ft., 2½-ft., 1 3/5-ft., 1 ½-ft., 1-ft. and other tone signals. Moreover, the present invention includes also a coupler system in which any suitable sampling circuit is employed in lieu of the sampling circuit described in the specification.

What is claimed is:

1. An electronic musical instrument employing a sampling system as a coupler comprising
  - a plurality of tone generators each having an output terminal at which a tone signal is generated,
  - a plurality of square waveform voltage generator each having an output terminal at which a square waveform voltage having a predetermined amplitude and repetition frequency is generated, said square waveform generators including duty ratio varying means for varying the duty ratio of said square waveform voltage,
  - a plurality of sampling means each having input output and control terminals, the input terminal of each of said sampling means being coupled to a corresponding one of said tone generators, the control terminal of each of said sampling means being coupled to a corresponding one of said square waveform voltage generators, the signal generated at the output terminal of said sampling means having a frequency corresponding to the signal applied to the input terminal but having a magnitude and amplitude determined by the duty ratio of the coupled square waveform voltage generator,
  - a plurality of coupling means each having at least two inputs respectively coupled to the output terminals of at least two of said sampling means and an output, and
  - e. means for obtaining a musical tone by receiving the signal at the output of said coupling means.
2. An electronic musical instrument as claimed in claim 1, which further comprises integrators connected between respective said sampling means and said coupling means and in which the sampled tone signal derived from said sampling means is supplied to said means for obtaining a musical tone through said integrator together with other sampled tone signals to be coupled with said tone signal.

3. An electronic musical instrument as claimed in claim 1, which further comprises a common integrator connected between said coupling means and said means for obtaining a musical tone and in which said sampling means are provided for respective said tone signals to be coupled together so as to receive said tone signal, and the sampled tone signals derived from said sampling means are coupled together to be supplied to said means for obtaining a musical tone through said common integrator. 5

4. An electronic musical instrument as claimed in claim 1, in which said square waveform voltage has an amplitude greater than the maximum amplitude of said signal to be sampled. 10

5. An electronic musical instrument employing a sampling system as a coupler comprising 15

- a. a plurality of tone generators each having an output terminal at which a tone signal is generated,
- b. a plurality of square waveform voltage generators each having an output terminal at which a square waveform voltage having a predetermined amplitude and repetition frequency is generated, said square waveform generators including duty ratio varying means for varying the duty ratio of said square waveform voltage, 20
- c. a plurality of sampling means each having input, output and control terminals, the control terminal of each of said sampling means being coupled to a corresponding one of said square waveform voltage generators, the signal generated at the output terminal of said sampling means corresponding to the signal applied to the input terminal but having a magnitude determined by the duty ratio of the coupled square waveform voltage generator,
- d. a plurality of coupling means each having at least two inputs respectively coupled to the output terminals of at least two of said sampling means and an output terminal, and 30

e. a plurality of envelope circuits each having an input terminal connected to a corresponding one of a plurality of key switches and an output terminal connected to the input terminals of at least two of said sampling means for delivering a depression-responsive signal in response to closure of said key switch for applying said depression-responsive signal to said sampling means as said input signal,

f. a plurality of gate means each having an input terminal coupled to a corresponding one of said tone generators, an output terminal, and a control terminal connected to the output of a corresponding one of said coupling means for controlling the transmission of said tone signal to the output terminal of said gate means in response to the sampled depression-responsive signal, and

g. means coupled to the output terminals of said gate means to derive musical tones from the signals generated by said tone generators and passed by said gate means.

6. An electronic musical instrument as claimed in claim 5, in which said envelope circuits are disposed in each section of a keyboard which is divided into at least two sections, and said sampling means are disposed in the depression-responsive signal transmission passages corresponding to the tone signals to be coupled together thereby attaining the coupling of the tone signals produced from the divided keyboard sections. 25

7. An electronic musical instrument as claimed in claim 5, in which each of said envelope circuits includes means for varying the magnitude of the signal output depending on the speed with which the key is depressed. 30

8. An electronic musical instrument as claimed in claim 5, in which said square waveform voltage has an amplitude greater than the maximum amplitude of said signal to be sampled. 35
